UNITED STATES PATENT OFFICE.

OSCAR HITT, OF WEEHAWKEN, NEW JERSEY.

DESIGN FOR A TOY AUTOMOBILE.

Application filed February 10, 1927. Serial No. 20,677. Term of patent 7 years.

To all whom it may concern:

Be it known that I, OSCAR HITT, a citizen of the United States of America, residing at Weehawken, in the county of Hudson and State of New Jersey, have invented a new, original, and ornamental Design for a Toy Automobile, of which the following is a specification, reference being had to the accompanying drawing, forming a part thereof, and showing a perspective view of the toy automobile embodying my design.

I claim:

The ornamental design for a toy automobile substantially as shown.
